UNITED STATES PATENT OFFICE.

WILLIAM SANDERS AND WALTER SELLEY, OF MANCHESTER, ASSIGNEES TO
THE FOLDING BOX MANUFACTURING COMPANY, LIMITED, OF LONDON,
ENGLAND.

FOLDING BOX.

SPECIFICATION forming part of Letters Patent No. 538,847, dated May 7, 1895.

Application filed July 16, 1894. Serial No. 517,766. (Model.) Patented in England October 27, 1892, No. 19,279; in France October 3, 1893, No. 233,187; in Belgium October 3, 1893, No. 106,610, and in Austria-Hungary February 23, 1894, No. 54,279 and No. 79,363.

To all whom it may concern:

Be it known that we, WILLIAM SANDERS and WALTER SELLEY, subjects of the Queen of Great Britain, residing at Manchester, in the county of Lancaster, England, have invented new and useful Improvements in Folding Boxes, (for which we have obtained a patent in England, No. 19,279, dated October 27, 1892; in France, No. 233,187, dated October 3, 1893; in Belgium, No. 106,610, dated October 3, 1893, and in Austria-Hungary, No. 54,279 and No. 79,363, dated February 23, 1894,) of which the following is a specification.

This invention has for its object, first, to provide a box for holding millinery, drapery, hats, wreaths, or other light goods or articles, which can be readily folded up, when empty and thus save room in storage or transit and be expanded for use as the case may be required; secondly, to provide such box with means which will serve both as a fastening for the lid and as a handle to carry or lift the box. We attain these objects by the means illustrated in the accompanying two sheets of drawings, in which—

Figure 1, Sheet I, is a perspective view of our improved folding box shown extended. Fig. 2 is a plan of the lid with the body of the box folded inside thereof. Fig. 3, Sheet II, is a vertical section, and Fig. 4 a plan with the lid removed. Fig. 5 is a detail view of the body-blank before folding—that is, with both the sides and end flaps being spread out flat; and Fig. 6 is a view of the internal frame.

Similar letters refer to similar parts throughout the several views.

In carrying out our invention we provide a flexible bottom *a*, to which the sides or ends are connected, this bottom consisting preferably of a suitable fabric. Two of the walls, in the present case the two end walls, are formed divided or in two parts *b* *b'* and are hinged to the other two walls or sides by a suitable hinge such as a fabric extending across the line of junction *d*. The divided or two part walls or ends *b* *b'* being unconnected, or connected only by a suitable hinge of fabric similar to that described and shown at *d'*

Figs. 1 and 4 may be folded inward against the inner faces of the side walls, the flexible bottom permitting this movement but preventing any outward movement of the said ends when the box is unfolded. The sides and ends are further retained against bulging outward by the cover *f* which overlaps the upper edges thereof, and the ends are kept from folding inward by a suitable frame *e*, of wire or the like which is placed upon the bottom of the box.

When the box is to be folded the frame is removed and the ends swung inward against the sides to permit the said sides to be folded down flat as before described, in which position the box and frame may be placed within the inverted cover as shown in Fig. 2.

In order to provide a combined handle and cover fastening means, we provide four apertures *h*, *h* in each end of the box, and two other apertures *h'* *h'* directly above these and slightly below the edge of the cover. A looped cord *g* is passed through the two holes *h*, *h*, from the outside, and thence the cord extends out through the holes or apertures *h'* *h'* and from there over the cover of the box to the opposite end where it is passed in through the corresponding holes *h'* and out through the lower holes *h*, its ends being connected to form an endless loop. The loop is of sufficient length so that when the portions *g'* are drawn tightly down upon the cover a slightly loose portion *i* will be provided at each end, and these portions may be drawn up and hooked over buttons *k* upon the ends of the cover, thus serving to securely hold the cover in place while the portions *g'* form a convenient handle.

When the cover is to be removed the portions *i* are unhooked from the buttons and permitted to drop down into the position shown in dotted lines at *i'* and this loosens the cord sufficiently to permit it to be drawn from the cover over the sides in the position shown by dotted lines *g'*. The stretcher frame is composed of open work or is of skeleton form.

What we claim as our invention, and desire to secure by Letters Patent, is—

1. In combination in a folding box, the bottom, the sides c, c' , the folding sides b, b' , each extending half way across the end of the box and being adapted to be folded against the sides c, c' , the bottom composed of flexible material capable of being folded and the frame e arranged on the bottom and fitting against the sides c, c', b, b' , the said frame being of open work or of skeleton form, substantially as described.
2. In combination in a folding box, the bottom, the folding sides, the cover having the buttons thereon and the cord having its looped ends engaging the buttons extending down therefrom through two holes in the folding sides thence within the box and out through a second pair of holes in the said sides and thence over the top of the cover in two strands substantially as described.
3. In combination, the box comprising the sides c, c' , and the folding sides b, b' , each of the latter extending half way across the end of the box, the cover fitting down over the sides, the buttons on the cover and the cord

having its looped ends engaging the cover, one strand of the loop passing through an opening in one folding side and the other strand through the other folding side and said strands passing thence over the cover of the box, substantially as described.

4. A collapsible box made up of two opposing sides c, c' and the ends each of the latter having the two flaps b, b' , the flexible bottom connecting the sides and flaps and the stretcher frame arranged within the box and bearing on the sides and end flaps, the said flaps being adapted to fold inward against the sides which latter are adapted to be superposed and the flexible bottom being arranged to be folded by the turning in of the end flaps to lie between the superposed sides, substantially as described.

WILLIAM SANDERS.
WALTER SELLEY.
